Attorney.

UNITED STATES PATENT OFFICE.

MICHAEL C. ARMOUR, OF CHICAGO, ILLINOIS.

STOVE.

SPECIFICATION forming part of Letters Patent No. 284,113, dated August 28, 1883.

Application filed February 24, 1883. (No model.)

To all whom it may concern:

Be it known that I, MICHAEL C. ARMOUR, a citizen of the United States, residing at Chicago, in the county of Cook and State of Illinois, have invented certain new and useful Improvements in Stoves, of which the following is a specification, reference being made to the accompanying drawings, in which—

Figure 1 is a vertical longitudinal section of the stove proper, and also of one of its lamps, the other lamp—that is, the one at the right—being shown in front elevation; and Fig. 2 is a plan view of the shelf which supports the lamps and oven, its supporting-rods and the legs of the stove being shown in plan section taken at the level of the top of said shelf.

My invention relates to stoves provided with two combustion apparatuses.

The object of my invention is to so construct a stove having two lamps, with a heating-chamber between them, as to render possible in a stove of this class the occasional arrangement of lamps in close proximity to each other, for the purpose of carrying on all the combustion possible directly under wash-boilers or other similarly long utensils or articles which it is desired to heat, and which are so extensive as to more than cover a single lamp.

In the drawings, which illustrate one embodiment of my invention, and will now be particularly described, A represents a horizontal flue, which forms the top of the stove, and is supported on legs a. This flue A is provided with rectangular covers B at each end, which are themselves provided with vessel-openings, and covers b for the same. Between these covers B, the stove-top is formed of a skeleton cover, B' formed of bars b', connected together by suitable cross-bars, the bars b' projecting above the general level of the top of the stove to insure the escape of the products of combustion—that is, of the combustion-current. The plates B and B' are all removable and interchangeable, and as these plates B and B' abut against each other, when two are removed which are adjacent to each other the opening in the top is long enough to receive instead large vessels—such as wash-boilers—which may thus be exposed directly

to contact with the combustion-current by making such boiler, for the time being and to the extent to which it is substituted, itself the top of the horizontal flue. 50

C is a shelf, supported at its ends by the stove-legs a, and at intermediate points between the recesses cut in said shelf for the reception of the reservoirs of the lamps, by suspension-rods c, depending from the stove-top A. Within these recesses of the shelf C are received the reservoirs d of the removable lamps D, the reservoir being of a width which about equals that of said recesses, the side edges of the latter forming guides, by which the position of the lamps relatively to each other is regulated. The tops of the reservoirs 60 project at each side, as shown in Fig. 1, in a lip or flange, which supports the lamp. The object of recessing the shelf C is to allow of its being located high enough above the bottom of the lamp to place the removable oven, or 70 whatever else may be upon it to be heated, more nearly on a level with the chimneys, and consequently nearer to that position where the radiated heat can be best utilized. The top of the lamp—by which is meant the tops of the 75 chimneys d' thereof—is provided with a plate, d', at suitable openings, in which the top of each chimney terminates, and which plate d' is provided with upwardly-projecting posts or protuberances d'', by means of which the continuity 80 and escape of the combustion-current is insured when the lamp is entirely removed from the stove proper and used independently—as a separate stove in itself—to support and heat upon its top cooking utensils. To provide for 85 the close connection of the lamp with the stove proper and still retain these protuberances d'', for the purpose aforesaid, three flanges, a'', are provided, each of which depends from the bottom of the horizontal flue A, around the back 90 and sides of a rectangular opening therein, and each of which flanges a'' corresponds in position and general appearance with the recesses in the shelf C, each of said flanges a'' thus forming a chamber, the fourth or front side of which 95 is formed, when the lamp is in place in the stove, by an upwardly-projecting flange, d'', rising from the top of the oven, or the top of the

lamp, as the case may be, which flange d^4 forms a close joint with the front ends of the depending flange a^2 by sliding in between them. This is shown in the right of Fig. 1, except that the 5 opposite sides of the depending flange a^2 , which are throughout at right angles to the flange d^4 , are shown in section. When the oven is slid in endwise at the end of the stove, (as herein-after described,) its flange will project up be- 10 tween the stove-legs a and the end of the horizontal flue A , and will thus be no hindrance to that endwise passage of the oven between the guides c' and c^2 , herein-after mentioned.

Between the lamps there is a rectangular 15 warming-oven, E , of ordinary construction, though the ends of the same next to the lamps are without walls and entirely open. This oven E is removable, as well as the lamps, by simply sliding it horizontally out at the front 20 of the stove, during which operation it is guided by the flanges c' , cast on the shelf C . The depth of the oven from front to back (outside measurement) about equals the distance be- 25 tween one of the flanges c^2 and the nearest flange c' .

From all the foregoing it will be perceived that when desirable one of the lamps may be substituted for the oven, the latter, if it is not entirely removed from the stove, being capa- 30 ble of sliding in endwise between the flange c^2 and the nearest flange c' , where it will be out of the way.

The object of adapting the stove for the re- 35 ception of lamps in three different places is that, if desired, a third lamp may be inserted in the space between the two outer lamps, which is usually used for warming food, and is shown in the drawings as especially adapted to that purpose through the intervention of 40 the removable oven.

The object of making the lamps, or at least one of them, interchangeable with the oven is to provide, without the use of a third lamp, for bringing the combustion-currents from both 45 lamps into direct contact with the bottoms of utensils—such as wash-boilers—which are not long enough to extend over both lamps when the latter are separated by an intervening oven, and even when the top of the horizontal 50 flue is not removed it is of course a great ad- vantage to be able to place all of the boiler di- rectly over the combustion apparatuses.

The object of using two combustion appara- 55 tuses—one at each side of an oven—instead of a single combustion apparatus at one side, is of course that the heat is more evenly distributed in said oven, and is too obvious to require elaboration here.

I do not here claim, broadly, either a re-

movable oven, a removable lamp, or a stove 60 having a removable lamp at each end and an oven between them; but,

Having thus described my invention, what I claim as new, and desire to secure by Letters Patent, is—

1. A stove provided with lamps and a space 70 between two of said lamps, combined with an oven placed within said space and adapted to be removed therefrom, substantially as set forth.

2. A stove provided with removable lamps and a space between two of said lamps, com- 75 bined with a shelf at the bottom of said space, said shelf being recessed to allow a lamp to be slid in and held thereby, substantially as set forth.

3. A stove provided with lamps and hav- 80 ing a space between two of said lamps, com- bined with an oven supported within the space and having an open end adjacent to each of said two lamps, the oven being removable from the space, substantially as set forth.

4. In a stove, the combination of lamps, a removable oven supported between two of said lamps, and a shelf at the bottom of said space, 85 having flanges to guide the oven as it is inserted within and drawn from the space, sub- stantially as set forth.

5. The combination, in a stove, of a lamp at each end thereof, and a sliding or remova- 90 ble oven having an open end confronting each of said lamps, substantially as said forth.

6. The combination, in a stove, of a lamp at each end thereof, and a shelf forming the bottom of the spaces for the lamps and of an 95 intermediate space, said shelf being recessed for the reception of each end lamp, and also recessed centrally to receive a lamp in the intermediate space, substantially as set forth.

7. A stove having a shelf, C , below the stove- 100 top and above the level of the bottom of the lamps, whereby a removable oven or other ar- ticles placed on said shelf to be heated will be more nearly on a level with the lamp-chim- neys, said shelf being provided at its center 105 with a recess through which the lower part of a removable lamp, used in place of said oven, or other articles at the center of the stove, will project, whereby the occasional presence of said removable lamp in said central position 110 and between the stove-top and said shelf is rendered possible, substantially as and for the purpose set forth.

MICHAEL C. ARMOUR.
